UNITED STATES PATENT OFFICE.

JOSEPH ROSZMANN, OF COVINGTON, KENTUCKY.

PERMUTATION LOCK.

Application filed December 3, 1921. Serial No. 519,599.

To all whom it may concern:

Be it known that I, JOSEPH ROSZMANN, a citizen of the United States, residing at Covington, in the county of Kenton and State of Kentucky, have invented certain new and useful Improvements in Permutation Locks, of which the following is a specification.

My invention relates to permutation locks exemplified as applied for locking the steering wheel of an automobile, although it is obvious that the same may be applied in other relations.

It is the object of my invention to provide a novel permutation lock employing tumblers arranged in lateral relation to each other, acting separately upon a slideable bolt for locking the same, and arranged to be placed in such relation as to release the bolt; further, to provide a series of laterally arranged tumblers having formations thereon for placing the tumblers in locking or unlocking relation, and positioning means for the respective tumblers for yieldably holding the same in positioned relations, and knobs for operating the tumblers; further, to provide a slideable bolt and laterally arranged tumblers for locking or unlocking the bolt, and an actuating lever for the bolt arranged to hold the same in locked relation or in unlocked relation.

The invention will be further readily understood from the following description and claims, and from the drawings, in which latter:

Fig. 1 is a side elevation of my improved device shown applied to the steering post and steering wheel of an automobile.

Fig. 2 is a front elevation of the same.

Fig. 3 is an axial section taken on the line 3—3 of Fig. 2.

Fig. 4 is a bottom view of the locking ring in connection with the device, shown in cross-section on the line 4—4 of Fig. 1.

Fig. 5 is a detail of the attaching means, taken on the line 5—5 of Fig. 2.

Fig. 6 is a detail of the assembling means for the lock, taken on the line 6—6 of Fig. 2.

Fig. 7 is a side elevation of my improved device, in locked relation, with the side wall 50 of the casing removed for exposing the interior of the casing.

Fig. 8 is a similar view, showing the device in unlocked relation.

Fig. 9 is a vertical section of my improved device, taken on the line 9—9 of Fig. 7.

Fig. 10 is a rear elevation of my improved

device, with the bolt-slide removed and the rear wall of the casing broken away for exposure of the inner ends of the tumblers.

Fig. 11 is a cross-section of my improved device, taken on the line 11—11 of Fig. 2; and,

Fig. 12 is an end elevation of the same, with the steering post partly broken away.

The steering post, shown at 21, is arranged to be stationarily secured to an automobile, and to extend in suitable direction in any usual manner. The steering shaft is shown at 22. A steering wheel 23 is secured to the steering shaft in any suitable manner so as to rotate with relation to the steering post, but to be held in endwise relation thereto.

A locking ring 26 is provided with a suitable number of recesses 27, which form keepers for the lock and which are also shown arranged to receive screws 28, by means of which to secure the ring to the steering wheel.

The casing of the lock is exemplified as comprising a box-like structure 31, provided with flanges 32. A rear plate 33 closes the casing. The flanges and rear plate are shown curved to fit the steering post. The casing and the rear plate are secured together, as by means of screws 34 received through the flanges 32 and threaded into the rear plate, these screws being shown as countersunk in the flanges in Fig. 6. Screws 35 are received through the flanges and the margins of the rear plate, and are threaded into the steering post for securing the lock to the steering post. These screws are also shown as counter-sunk in the flanges in Fig. 5. A suitable finish coating 36 covers the casing and the screw-heads, which are flush with the surface of the flanges, so as to cover and hide the screws.

A bolt-slide 41 has a bolt 42 thereon. This bolt-slide is arranged to slide in the casing, and is normally urged into locking relation by a spring 43, one end of which is received in a recess 44 in the bolt-slide, the other end of the spring resting against the end wall 45 of the casing. The rear face of the bolt-slide is shown curved on an arc to correspond to the curvature of the rear plate, and the front of the bolt-slide is at its corners provided with lugs 46, by means of which the bolt-slide is guided on the front wall 47 of the casing.

There is a channel 51 extending lengthwise in the middle portion of the front face of the bolt-slide. A permutation plate 52

extends across this channel, and is fixed to the side walls 53 of the channel by means of screws 54. This permutation plate is provided with slots 55 and with enlargements 56 of the slots.

A series of tumblers 59 is provided, shown in lateral arrangement, and instanced as superposed. The tumblers are shown comprising round stems 60, reduced in diameter 10 at points corresponding in position with the slots in the permutation plate, as by providing the sides of the tumblers with indentations 61 to form shanks 62, having flanges 63 at their inner ends.

15 Socket-pieces 65 are fixed in apertures 66 in the front wall 47 of the casing. These socket-pieces are rigidly positioned in the front wall, as by brazing or otherwise fixing the same thereto. The inner ends of these 20 socket-pieces are provided with slots 68 radially arranged with relation to the inner walls of the sockets. Each of the permutation stems is provided with a pin 69, which is arranged to be selectively placed in any 25 of the slots at the rear of the socket-pieces for determining the relations of the tumblers to the tumbler-plate. Each of the tumblers has a knob 70 fixed to its outer end, shown as a knurled knob, for turning the tumbler.

30 A spring 73 is located in each of the sockets of the socket-pieces between the bottom of the socket and an enlargement 74 of the stem, (see Fig. 11), which is received in and guided by the wall of the socket. This 35 construction is for the purpose of positioning the tumbler in adjusted relations by yieldingly pressing the tumbler outwardly for normally urging the pin thereon to enter one of the slots, and to permit the yielding inward movement of the tumbler to move the pin out of the slot when the knob of the tumbler is to be turned.

The shanks of the tumblers are wider in one dimension than in the other, so that when 45 any one of the shanks is placed crosswise in its enlargement in the slot of the permutation plate, the lock is in locked relation. In order to place the lock in unlocked relation, all of the shanks must in their greater dimensions be parallel with the slot in the 50 permutation plate.

Each of the knobs is provided with an identifying mark 76 to show the turned relation of the tumbler. These identifying 55 marks are shown as digits. Some of the shanks in their greater dimensions are placed in relations similar to the digits, and some are placed crosswise thereof, depending on the arrangement desired for open relation of 60 the lock. In the present exemplification the shanks of the tumblers marked 1, 3, 5 and 6 extend lengthwise of the digits, and the shanks of the tumblers marked 2 and 4 extend crosswise of the digits.

65 The arrangement of the tumblers shown

in Fig. 1 is duplicated in Figs. 3, 7, 9 and 10, being a locked relation of the lock. The unlocked relation of the lock in the present exemplification is had by turning the tumblers 2 and 4 to place the digits 2 and 4 70 crosswise, whereby the shanks of said tumblers 2 and 4 are arranged lengthwise of the slot in the slot in the plate, thereby placing all of said shanks lengthwise of said slot, as shown in Fig. 8. When all of the shanks 75 are so arranged the bolt-slide may be operated to retract the bolt.

The retraction of the bolt is effected by means of a lever, comprising a stem 81, rotating in a bearing 82 in the wall of the casing, and having an arm 83 fixed thereto, and operated by means of a knob 84 fixed to the shank. The arm 83 is received in a recess 85 in the side of the bolt-slide, and is arranged to engage the end walls 86, 87, of 85 said recess for moving the bolt-slide. These end walls comprise cam-portions arranged to be engaged by the end of the arm for moving the bolt-slide, shoulders 88, 89, being located at the ends of said cam-portions for 90 arresting the movements of the arm. When the arm is in engagement with a shoulder, the bolt-slide is held in moved relation, so that the operating knob may be released by the operator, and the bolt remain in the 95 relation in which it has been placed by said knob.

When the bolt is in unlocked relation, all of the shanks of the various tumblers are located in the slots in the rear of the tumbler 100 plate, thereby preventing turning of any of the tumblers while the lock is in unlocked relation, and avoiding the necessity or rearranging the tumblers if it is desired to again lock the lock. The bolt is again placed 105 in locking relation by the turning of the operating knob, and the lock may thereupon be locked by the turning of any one or more or all of the tumblers, making it necessary to again manipulate the tumblers into correct relations to again permit the retraction of the bolt.

A great number of different combinations in unlocking relation of the lock may be obtained by change in relation of one or more 115 of the digit knobs and their respective shanks, or the substitution of tumblers having different relation of digit and shank.

My improved device forms a simple and exceptionally strong lock of few and simple 120 parts, readily made and assembled.

Having thus fully described my invention, what I claim as new and desire to secure by Letters Patent, is:

1. In a permutation lock, the combination 125 of a bolt-slide provided with slots and enlargements of said slots, and rotatable tumblers provided with shanks in alinement with said slots and said enlargements, said respective shanks being wider in one dimen- 130

sion than in another dimension, said wider dimensions being wider than said slots and arranged to be located in said enlargements crosswise of said slots when said bolt-slide 5 is in locked relation, said shanks arranged to be rotated for presenting their wider dimensions or their narrower dimensions toward said slots, means for yieldingly holding said respective tumblers in rotated relation, and spring means normally urging said bolt-slide into locked relation.

2. In a permutation lock, the combination of a permutation-plate provided with a slot extending lengthwise thereof and provided with enlargements to divide said slot into sections, tumblers in lateral arrangement, said tumblers respectively provided with shanks respectively wider in one dimension than in another dimension and located in said enlargements when said permutation-plate is in locking relation, said wider dimensions being wider than said slots, said tumblers arranged to be rotated for placing the narrower dimensions thereof 20 25 in alinement with said slot, and means to move said permutation-plate lengthwise when said narrower dimensions are in said last-named relation to place the walls of said sections of said slot alongside said narrower dimensions for unlocking relation of said permutation-plate,

3. In a permutation lock, the combination of a permutation-plate, said permutation-plate provided with slots and enlargements 30 35 of said slots, laterally arranged rotatable tumblers, respectively comprising stems and knobs, said stems comprising shanks respectively wider in one dimension than in another dimension, said wider dimensions being wider than said slots, and said slots co-

operating with the narrower dimensions of said shanks for unlocking relation of the lock, socket-pieces through which said stems respectively extend, said stems respectively provided with abutments, and springs in 45 said socket-pieces about said stems between the bottoms of said socket-pieces and said knobs to urge said abutments toward said socket-pieces and to hold said tumblers in rotated relations.

4. In a permutation lock, the combination of a casing, a bolt-slide therein, a permutation-plate on said bolt-slide, said permutation-plate provided with slots and enlargements of said slots, laterally arranged rotatable tumblers respectively comprising stems and knobs, said stems comprising shanks respectively wider in one dimension than in another dimension, said wider dimensions being wider than said slots and 60 said slots co-operating with the narrower dimensions of said shanks for unlocking relation of said lock, socket-pieces fixed to said casing, said stems extending through said socket-pieces, the inner ends of said 65 socket-pieces provided with slots, pins in said stems between said socket-pieces and said shanks, and springs in said socket-pieces under said knobs to urge said tumblers outwardly and said pins into 70 said last-named slots to hold said tumblers in rotated relations.

In testimony whereof, I have hereunto signed my name in the presence of two subscribing witnesses.

JOSEPH ROSZMANN.

In presence of—

HENRY J. WELLER,
DELMA WERNsing.
